United States Patent Office

Des. 214,172
Patented May 20, 1969

214,172

VASE OR SIMILAR ARTICLE

Lena L. Troutman, 418 W. Monroe,
Salisbury, N.C. 28144

Filed July 10, 1968, Ser. No. 12,678

Term of patent 14 years

Int. Cl. D11—02

U.S. Cl. D29—28

Fig. 1.

Fig. 2.

Fig. 4.

Fig. 3.

FIG. 2 is a top plan view thereof.

FIG. 3 is a rear view as viewed on line 3—3 of FIG. 4 thereof.

FIG. 4 is a side elevational view as viewed on line 4—4 of FIG. 1, and

FIG. 5 is a fragmentary cross-sectional view taken on line 5—5 of FIG. 3 thereof.

I claim:

The ornamental design for a vase or similar article, substantially as shown.
